UNITED STATES PATENT OFFICE.

SAMUEL R. PAYNE, OF QUINCY, ILLINOIS, ASSIGNOR TO U. S. SAFETY FIRST GATE CORPORATION, OF QUINCY, ILLINOIS.

GATE AND GATE-OPERATING MECHANISM FOR RAILWAY CROSSINGS.

Application filed August 29, 1922. Serial No. 585,058.

To all whom it may concern:

Be it known that I, SAMUEL R. PAYNE, a citizen of the United States, residing at Quincy, in the county of Adams and State 5 of Illinois, have invented certain new and useful Improvements in Gates and Gate-Operating Mechanisms for Railway Crossings, of which the following is a specification, reference being had to the accompanying drawings.

This invention relates to gates for railway crossings, and particularly to railway gates for use at grade crossings, the primary object of this invention being to improve upon and simplify the construction 15 illustrated in my Patent No. 1,261,433, of April 2, 1918.

A further object is to reduce the number of parts necessary to operate the gate, render the gate more practical, and cause the same to work more efficiently.

A still further object is to provide a construction of this character wherein the gate is normally held in its raised position by a 25 counter weight or equivalent element but wherein upon the approach of a train toward the crossing and within a predetermined distance thereof, the train by engagement with a series of ramps mounted upon the track will cause the depression of the gate to a horizontal position, the gate being held depressed until the train reaches and moves across the crossing, the gate then being released and returning to its vertical position, the ramps on one side of the crossing being returned to their normal position as soon as the train leaves them and the ramps on the other side of the crossing being held depressed by the train as it moves 35 away from the crossing but returning to their normal positions when the train leaves the ramps.

Still another object is to provide a crossing gate of the character stated wherein the 45 barrier forming part of the gate is mounted so that if a vehicle gets caught between the two gates the vehicle may move onward and will open the carrier to permit the vehicle to pass off of the crossing, the barrier then returning to its closed position.

Other objects will appear in the course of the following description.

My invention is illustrated in the accompanying drawings, wherein:—

55 Figure 1 is a side elevation of a railway

gate and a portion of the track adjacent thereto constructed in accordance with my invention;

Figure 2 is a top plan view of the construction shown in Fig. 1;

Figure 3 is an enlarged side elevation of the ramps and allied parts, the shafts 25, 31 and 36 being shown in section;

Figure 4 is a top plan view of the construction shown in Figure 3 partially broken 65 away;

Figure 5 is a side elevation of the yokes 51 and 51^a, the pin 53 and shaft 31 being in section;

Figure 6 is a side elevation of the barrier 70 and barrier operating mechanism, the shafts being in section;

Figure 7 is a fragmentary top plan view showing the barrier lowered and in dotted lines showing the barrier swinging outward;

Figure 8 is a front elevation of the construction shown in Figure 1, part of the barrier and the member 15 being in section;

Figure 9 is a perspective view of the lever 29 and the means for operating it;

Figures 10 and 11 are elevations of the mechanism shown in Figure 9, showing the two positions of the parts and showing the shafts in section.

In the drawings, A designates a track having the track rails *a*, and B designates the highway intersecting the rails at the crossing. Disposed at the crossing and on one side of the highway and on each side of the rails *a* are the railway gates, each of these 85 gates consisting of a base or standard and a barrier pivotally mounted thereon. Each gate is constructed in the same manner and, therefore, a description of one gate will suffice for both.

Referring to Figure 6, it will be seen that the standard or base consists of a casting 10 which may be made in two half sections or in any other suitable manner, this casting being angular in form and having a base 11 100 which is suitably mounted upon a foundation. This casting 10 or standard is hollow so as to house the several gears herein-after described. Extending through the standard 10 is a shaft 12 which is disposed 105 approximately at the intersection of the vertical portion of the standard with the horizontal portion 13 thereof. Mounted upon this shaft 12 to rotate therewith is a sector gear 14 having a radial extension 15 110

U-shaped in cross section. Passing through this extension is a bolt 16, and mounted upon this bolt is the barrier 17, which may be of any suitable form and either of wood or metal. This barrier 17 is so mounted upon the bolt 16 that it may oscillate. In other words, it is hinged to the portion 15. A spring 18 surrounds this bolt, one end of the spring being fixed in any suitable manner, 10 the opposite end 19 of the spring being engaged with the barrier 17. This spring, therefore, serves to hold the barrier 17 in line with the socket or extension 15 but permits the barrier 17 to swing outward when 15 the barrier is in a horizontal position like a door. This barrier is free to swing, it will be understood, in one direction but is limited in the other direction by contact with the rear wall of the socket 15.

20 The sector gear 14 meshes with a pinion 20 mounted upon a shaft 21, and this pinion in turn meshes with a sector gear 22 carried by and forming part of a counterweight arm 23 mounted upon a shaft 24 extending 25 through the portion 13 of the standard. It will thus be seen that when the socket 15 and the barrier move downward to a horizontal position from a vertical position, the weight 23 will be raised, and that if the gate be then 30 released the weight 23 will cause the barrier to return to its vertical position.

For the purpose of operating the sector gear 14, I provide a shaft 25 mounted in the base of the standard 10 and carrying a gear 35 wheel 26. This gear wheel may be operatively connected to the shaft 12 in any suitable manner, but I have illustrated a train 40 of three gear wheels 27 mounted upon shafts 28 and meshing with each other, the end gear wheels meshing respectively with the gear wheels 26 and 14. These gear wheels have such ratio that a predetermined rotation of 45 the gear wheel 26 in one direction will cause a quarter turn of the sector gear 14 so as to carry the barrier 17 from its vertical to its horizontal position and vice versa.

As before remarked, I do not wish to be limited to the specific means illustrated whereby power is conducted from the gear 50 wheel 26 to the sector gear 14, as other means might be used for the purpose. Thus the two shafts 12 and 25 might be connected by sprocket chains or by rack and pinion or a variety of different mechanisms might be used to transmit power and motion. The shaft 25 carries upon it at a point somewhat 55 remote from the barrier and adjacent one of the rails *a* the arm 29 having a curved inner face 30. This arm 29 has a relatively wide face and extending parallel to the shaft 25 60 is a shaft 31 which carries upon it a gear wheel 32 or sector gear having a tangentially extending arm 33 formed with a roller 35 at its outer end, this outer end being angularly bent so that the roller 35 bears

against one portion of the curved face 30 of the arm 29.

Disposed above the shaft 31 and parallel thereto is a shaft 36, this shaft carrying on it a gear wheel 37 meshing with a gear wheel 32 and having an arm 38 extending radially therefrom and carrying at its end the roller 39 which also bears against the convex face 30 of the arm 29. It will be seen now that when the shaft 31 is given a counter-clockwise rotative movement, the roller 35 will bear against the outer end of the arm 29 and turn this arm downward from the position shown in Figure 9 to an approximately horizontal position. The intermeshing gear 70 wheels 32 and 37 will cause the arm 38, however, to turn in the opposite direction and away from the arm 39. If, however, a rotation is communicated to shaft 36 in a counter-clockwise direction, the arm 38 will move 75 downward and bear down upon the arm 29 and rotate shaft 25, while the arm 33 will move in the opposite direction.

Thus, an oscillation in a counter-clockwise direction of either the shaft 36 or the shaft 90 31 will cause the operation of the arm 29, and if the shaft 31 is given a rotation in a counter-clockwise direction, the arm 33 operates to depress arm 29 and if it is given a rotation in a clockwise direction the arm 38 95 will operate against arm 29 and rotate the shaft 25. Thus the rotation of the shaft 31 in either direction from its neutral position will cause the depression of the outer end 100 of the arm 29 and cause the lowering of the barrier from its vertical position to its horizontal position.

In order to provide means for operating the shaft 31 by the approach of a train toward the crossing, I mount beside the rails 105 *a* on each side of the crossing a series of ramps, each ramp of the series of ramps on one side of the crossing being designated 40 and each ramp of the series of ramps on the opposite side of the crossing being designated 40^a. The ramps on one side of the crossing are the same as the ramps on the opposite side of the crossing and each ramp is exactly like the other ramp. Therefore, a description of one will apply to the other. 110 Each ramp consists of an angular plate which is outwardly flanged at its upper end, as at 41. This flange is depressed or downwardly inclined at the outer ends of the ramp, as at 42, so that the tread of a railway 115 car wheel will ride on this inclined surface and gently depress the ramp so that the upper surface of the ramp will be on a level with the outer surface of the rail.

Each ramp is vertically slotted at a plurality of points, as at 40^b, and through these slots pass pins 43 which engage with the rail, these pins being headed at their outer ends. Mounted upon each pin is a lever 44 whose upper end carries a roller 45 normally bear- 120 125 130

ing beneath the flange 41. The lower end of the lever is pivotally connected by a pin 46 to a longitudinally extending rod 47. All of the ramps 40 are connected to the rod 47 and 5 all of the ramps 40^a are connected to a like rod 47^a. The ramps of a series are separated from each other by a short distance, but this distance is so short that a train or car approaching the highway crossing always has 10 one of its wheels depressing a ramp so that from the time the train arrives at the crossing one series of ramps is depressed.

The rod 47 of the ramps 40 is engaged by a contractile spring 48 which is disposed 15 adjacent the shaft 25, the inner end of this spring being anchored in any suitable manner and the other end being connected to the rod 47 in any suitable manner. Pivotally connected to the rod 47 adjacent spring 48 is 20 an angularly bent rod 49 formed in two sections connected by a turnbuckle 50. The outer section of this rod 49 terminates in a yoke 51, this yoke being slotted, as at 52. The rod 47^a is connected to a like spring 48 25 and is also pivotally connected to an angularly bent rod 49 having a turnbuckle 50 and terminates in a slotted yoke 51^a. These yokes 51 and 51^a overlap each other, as shown in Figure 5, and through these yokes 30 passes a pin 53. This pin 53 passes through the upper end of a crank 54 whose lower end is engaged with the shaft 31, see Figure 5.

It will be obvious now that if the ramps 40 be depressed they will rock the levers 44, pull 35 upon the rod 47 against the action of the spring 48, pull upon the yoke 51, and this will draw the upper end of the crank 54 from left to right in Figure 3, giving a clockwise rotation to shaft 31. This will cause the gear 40 wheel 32 to move in a clockwise direction and cause the gear 37 to move in a counterclockwise direction so that the arm 38 will depress the lever or arm 29 and move the shaft 25 in a counter-clockwise direction, which through 45 the action of the gear wheels previously described, will shift the barrier from its vertical to its horizontal position. Now when the rod 47 is drawn from left to right by the depression of the ramps 40, the movement of the pin 53 from left to right will pull upon the yoke 51^a, which in turn will pull upon the rod 47^a and this will shift the levers 44 associated with the rod 47^a and the ramps 40^a over to a position reverse to that in Figure 3, 50 thus lowering the ramps on that side of the highway, the spring 48 for this series of ramps contracting still further from its normal position to permit this movement and assisting in this movement.

60 Now when the train has reached the crossing and the rear end of the train has passed all of the ramps 40, the front end of the train will engage the ramps 40^a, but as soon as the rear end of the train has passed the ramps 40 65 and all these ramps are released, the spring

48 will act to draw these ramps 40 back again to their normal or raised position. Thus the yoke 51 will move from right to left without, however, affecting the yoke 51^a, which will remain shifted because of the depression of the ramps 40^a. When the train has left the ramps 40 and the ramps 40 have returned to their normal position, the movement of the yoke 51 will permit the counter-weights of the barrier to return it to its vertical position so that as soon as the train has reached or passed the crossing, the barrier will rise to its inoperative position. As soon as the train has cleared the ramps 40^a, 70 these ramps will return to their operative position, as shown in full lines in Figure 3. What occurs with a train moving from right to left in Figure 1 will also occur with a train moving from left to right, only in that case the ramps 40^a will be initially operated 75 and the rod 47^a will be initially operated, the pin 53 will be drawn from right to left by the movement of the yoke 51^a, the shaft 31 will be given a counter-clockwise movement, this will give a counter-clockwise movement 80 to the gear wheel 32, and the arm 33 will then act to depress the arm 29, oscillating the shaft 25, which through the train of gears, as before described, will lower the barrier to its horizontal position. 85

It will be seen that the mechanism which I have described is very simple and very positive in its action. The approach of a train in either direction will cause the barriers to lower and these barriers to 100 be raised as soon as the train has reached the crossing and is over the crossing to form a barrier to approaching vehicles. Thus the barriers do not remain lowered until the train has reached the trip mechanism 105 at a distance from the crossing with the consequent delay to traffic, but the barrier is immediately raised when the train has initially crossed the highway so that as soon as the tail end of the train has passed the highway, 110 traffic may be resumed.

While I have illustrated this invention as applied to a single track road, it is perfectly obvious that it may be applied to a double track road, the ramps 40 being applied to one track and on one side of the crossing, while the ramps 40^a are applied to the other track and on the opposite side of the crossing. Thus my mechanism is applicable either to a single track or double track 115 road and may be readily made applicable to any number of tracks intersecting the highway.

It will be seen by comparison with my former patent before referred to that I have 120 greatly simplified the mechanism thereof, reduced the number of parts, and rendered the action much more positive. The barrier is hinged to the socket 15 in order to eliminate danger or accident in case a vehicle or a per- 125

son gets in between the gates with an on-coming train. In that case the vehicle can push right through and will swing the barrier in a horizontal position and against the 5 action of the spring 18. As soon as the vehicle has gotten beyond the barrier, the spring 18 will cause the barrier to swing to its normal or closed position.

I claim:—

10. 1. A railway crossing gate, comprising a barrier movable from a vertical to a horizontal position, a counterweight urging the barrier to its vertical position, a sector gear operatively connected to the barrier to oscillate it, a shaft carrying a gear wheel operatively engaging the sector gear, two series of ramps disposed alongside the railway track and on each side of the highway crossing, said ramps being deppressible under 15 the weight of a train, means operatively connecting the ramps to said last named shaft to cause the rotation of the shaft in one direction upon the depression of either series of ramps, and means permitting the return 20 of one series of ramps to its normal position and the return of the barrier to its normal position when the train leaves one series of ramps and engages the other series of ramps.
25. 2. A railway crossing gate, comprising a barrier normally urged to a vertical position but deppressible to a horizontal position, two series of ramps, both series being disposed along a rail of the track and one series being disposed on one side of the crossing and the other on the opposite side of the crossing, means urging both series of ramps upward, means acting upon the depression of either series of ramps under 30 the weight of a train to cause the depression of the barrier to its horizontal position and the depression of the other series of ramps, said means permitting the upward movement of the first series of ramps and the movement 35 of the barrier to its vertical position when the train has left the first named series of ramps and engaged the second named series of ramps.
40. 3. A railway crossing gate, an operating mechanism therefor including a supporting standard, a shaft mounted therein and having a sector gear, a barrier attached to the sector gear to move therewith from a vertical to a horizontal position and vice versa, a sector gear having a counter-weighted arm, an intermediate gear between the two sector gears and operatively connecting them, an operating gear in the base of said standard, and operative connections between 45 said operating gear and one of said sector gears.
50. 4. A railway crossing gate, including a supporting standard, a shaft mounted therein and having a sector gear provided with a radially extending socket on one side, a

barrier hinged in said socket for movement in a plane at right angles to the plane of rotation of the sector gear, a spring yieldingly holding said barrier in a position in the plane of said sector gear, a counterweight 55 operatively engaging the sector gear to cause the return of the sector gear to its normal position and the lifting of the barrier to its vertical position, and train operated means disposed along the track on each side of the crossing to cause a predetermined rotation of said sector gear to lower the barrier upon the approach of a train.

5. A crossing gate, including a barrier mounted for movement from a vertical to a horizontal plane, a counterweight operatively connected to the barrier to urge it to a vertical plane, means for oscillating the barrier including an operating shaft therefor, an arm on the operating shaft, a pair of countershafts carrying intermeshing gears, each countershaft having an outwardly projecting arm engaging at its extremity with the arm on the operating shaft whereby a rotation of one of said countershafts in either direction will cause the depression of said operating arm, ramps mounted adjacent the rails of the track and on each side of the crossing, said ramps being deppressible under the weight of a train and being urged to an elevated position, and means operatively connecting the ramps on both sides of the crossing to one of said countershafts, said mechanism permitting the independent depression of the ramps.

6. A crossing gate, including a barrier mounted for movement from a vertical to a horizontal plane, a counterweight operatively connected to the barrier to urge it to a vertical plane, means for oscillating the barrier including an operating shaft therefor, an arm on the operating shaft, a pair of countershafts carrying intermeshing gears, each countershaft having an outwardly projecting arm engaging at its extremity with the arm on the operating shaft whereby a rotation of one of said countershafts in either direction will cause the depression of said operating arm, ramps mounted adjacent the rails of the track and on each side of the crossing, said ramps being deppressible under the weight of a train and being urged to an elevated position, and means operatively connecting the ramps on both side of the crossing to one of said countershafts, said mechanism permitting the independent depression of the ramps.

105. 7. A crossing gate, including a barrier mounted for movement from a vertical to a horizontal plane, a counterweight operatively connected to the barrier to urge it to a vertical plane, means for oscillating the barrier including an operating shaft therefor, an arm on the operating shaft, a pair of countershafts carrying intermeshing gears, each countershaft having an outwardly projecting arm engaging at its extremity with the arm on the operating shaft whereby a rotation of one of said countershafts in either direction will cause the depression of said operating arm, ramps mounted adjacent the rails of the track and on each side of the crossing, said ramps being deppressible under the weight of a train and being urged to an elevated position, means operatively connecting the ramps on both side of the crossing to one of said countershafts, said mechanism permitting the independent depression of the ramps, said mechanism including a crank arm connected to one of said countershafts and having a pin at its outer end, a pair of slotted yokes through which the pin projects, and a rod extending from each yoke and being operatively connected to a corresponding series of ramps.

110. 8. A crossing gate, including a barrier

- mounted for movement from a vertical to a horizontal plane, a counterweight operatively connected to the barrier to urge it to a vertical plane, means for oscillating the barrier including an operating shaft therefore, an arm on the operating shaft, a pair of countershafts carrying intermeshing gears, each countershaft having an outwardly projecting arm engaging at its extremity with the arm on the operating shaft whereby a rotation of one of said countershafts in either direction will cause the depression of said operating arm, ramps mounted adjacent the rails of the track and on each side of the crossing, said ramps being compressible under the weight of a train and being urged to an elevated position, means operatively connecting the ramps on both sides of the crossing to one of said countershafts, including a crank arm operatively connected to one of said countershafts and having a crank pin at its outer end, a pair of slotted yokes through which the crank pin passes, rods extending parallel to the rails and each beneath one series of ramps, said rods being mounted for longitudinal movement, levers each operatively pivoted at its lower end to the corresponding rod and having a roller at its upper end upon which the ramp rests, and independent springs connected to the said rods and drawing the rods toward each other and urging the levers toward a vertical position with the ramps raised, the ramps being guided for vertical movement under the weight of a train.
8. The combination with a crossing gate including a barrier movable from a vertical to a horizontal position and vice versa, and means urging the barrier to a vertical position, of train operated means for shifting the barrier to a horizontal position including an operating crank, having a crank pin, a pair of yokes slidably engaging the crank pin, the adjacent ends of the yokes normally being abutted against the crank pin, rods disposed alongside the rails of the track and extending in opposite directions on each side of the crossing, springs urging said rods toward each other, operative connections between said rods and said yokes, two series of ramps disposed on each side of the crossing and alongside the rails of the track, each ramp having an outwardly projecting flange at its upper edge and two series of levers pivotally supported at the sides of the rails of the track and beneath said ramps, each of the levers at its lower end being connected to a corresponding rod and at its upper end having a roller bearing against the under face of the ramp flange,

and springs normally supporting these levers in a slightly inclined position with the upper ends nearer the crossing than the lower ends.

9. A crossing gate including a barrier mounted for movement from an unobstructing to an obstructing position and vice versa, a shaft for operating the gate and having an outwardly projecting arm, a pair of counter-shafts carrying intermeshing gears, each counter-shaft having an outwardly projecting arm engaging at its extremity with the arm on the operating shaft whereby a rotation of one of said counter-shafts in either direction will cause the depression of said operating arm, and means mounted adjacent the rails of the track and on each side of the crossing and shiftable in one direction under the weight of a train, said means on both sides of the crossing being operatively connected to one of said countershafts and said means permitting the independent depression of the ramps.

10. A crossing gate including a barrier mounted for movement from an unobstructing to an obstructing position and vice versa, means urging the barrier to an unobstructing position, means for shifting the barrier including an operating shaft having an arm, a pair of counter-shafts carrying intermeshing gears, each counter-shaft having an outwardly projecting arm engaging at its extremity with the arm on the operating shaft whereby a rotation of one of said countershafts in either direction will cause the depression of said operating arms, ramps mounted adjacent the rails of the track and on each side of the crossing, the ramps being compressible under the weight of a train and being urged to an elevated position, and means operatively connecting the ramps on each side of the crossing to one of said counter-shafts, said means permitting the independent depression of the ramps.

11. In a railway crossing, a supporting standard, a shaft mounted therein and having a member carried thereby provided with a radially extending socket on one side face, a barrier hinged in said socket for movement in a plane at right angles to the plane of rotation of the shaft and member, means yieldingly holding said barrier in position in the plane of said member, and means whereby the barrier may be lowered or raised upon the approach or recession of a train.

In testimony whereof I hereunto affix my signature.

SAMUEL R. PAYNE
